AIR SWEPT BALL AND RING PULVERIZER
THROAT AND UPPER RING CONSTRUCTION

Walter C. King, Lancaster, S. C., and Lester L. Leach, Akron, Ohio, assignors to The Babcock & Wilcox Company, Rockleigh, N. J., a corporation of New Jersey

Application November 1, 1949, Serial No. 124,754

18 Claims. (Cl. 241—58)

1

The present invention relates in general to improvements in the construction and operation of pulverizers, and more particularly, to pulverizers of the general type shown in U. S. Patent No. 2,275,595 in which a housing encloses a horizontally arranged circular series of rolling grinding elements positioned between cooperating, relatively movable upper and lower grinding rings resiliently pressed together, the raw material to be pulverized being delivered to the inner side of the annular grinding zone, and most of the wholly or partly pulverized material swept up at the outer side of the grinding zone by a high velocity annular stream of a gaseous carrier medium passing upwardly through an annular throat. Any particles of sufficient density to drop through the throat against the carrier gas stream are collected in the subjacent part of the pulverizer. The pulverized material in suspension in the gaseous carrier medium is carried upwardly to a rotary classifier which operates to separate oversize material which returns by gravity towards the grinding zone, while the finer particles of material are discharged in suspension in the carrier medium from the classifier outlet through the housing pulverized material outlet to storage or a point of use.

The commercial value of pulverizers of the character described is dependent upon a number of factors including the original cost of the pulverizer and auxiliary equipment for a given output capacity, power consumption, fineness of output over the permissible load range, adaptability for operation with materials of different grindability, feed size and moisture content, the extent of the operating load range, and the amount of the recirculating load. The size and power requirements of the fan or blower will depend upon the pulverizer static pressure differential and quantity handled.

With pulverizers of the character illustrated in said U. S. Patent No. 2,275,595, it has now been found that the pulverizing capacity is limited by aeration and consequent fluidizing of the material in the grinding zone due to the direction of the gaseous carrier medium stream relative to the grinding zone, thus preventing the maximum utilization of the grinding capacity of the grinding parts, and the presence of a relatively dense slowly rotating annular mass of raw or partly pulverized particles at the outer side of the grinding zone believed to be due to accumulations in that area of oversize particles attempting to separate by gravity from the carrier gas stream, or rejected by the classifier and by-passing the

2

grinding zone. The presence of this suspended dense annular mass of particles around the outside of the grinding zone results in a relatively high static pressure differential through the pulverizer as the mass fills substantially all of the space between the housing and the grinding elements, thus materially obstructing the flow path of the rising carrier gas stream. The mass acts like a filter bed for the rising suspended particles, with some of the suspended oversize particles being caught in the mass and lighter particles in the mass being picked up in the gas stream. The carrier gas flow through the suspended mass is often non-uniform, as the gas stream will tend to follow the flow path of least resistance, resulting in an uneven peripheral distribution of the suspended particles to the rotary classifier. The flow obstructing effect of the suspended mass of particles also causes a portion of the rising carrier gas stream to flow inwardly through the row of rolling grinding elements, thus opposing the outward flow of pulverized material and effecting aeration of the material in the grinding zone. The material thus fluidized is difficult to pulverize by the normal grinding action of the relatively moving rolling grinding elements and rings as it tends to flow out of the path of the cooperating grinding parts.

The general object of the present invention is the provision of an improved construction and operation of a pulverizer of the general type described which is characterized by a substantial increase in pulverized material output capacity and a decrease in the static pressure differential through the pulverizer without any decrease in fineness of output or increase in pulverizer size or cost. A further and more specific object is the provision of a pulverizer of the type described with an improved construction and arrangement of the parts defining the flow path of the gaseous carrier medium adjacent the grinding zone, whereby the tendency towards the formation of an annular relatively dense mass of suspended oversize particles of pulverized material around the grinding zone is substantially eliminated, much of the oversize material leaving the grinding zone is immediately recirculated through the grinding zone, and aeration of the material in the grinding zone minimized. A still further specific object is an improved construction and arrangement of the non-rotary upper grinding ring, whereby the area available for reentrance to the grinding zone of material recirculated by the rising stream of carrier gas is substantially increased.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of our invention.

Of the drawings:

Fig. 1 is a sectional elevation of the pulverizer, taken on the line 1—1 of Fig. 2;

Fig. 2 is a plan section on a smaller scale taken on the line 2—2 of Fig. 1;

Fig. 3 is an enlarged view of a portion of Fig. 1;

Fig. 4 is a side view of one of the deflector plates taken on the line 4—4 of Fig. 3;

Fig. 5 is a plan view of the deflector plate taken on the line 5—5 of Fig. 3; and

Fig. 6 is a horizontal section through one of the classifier blades taken on the line 6—6 of Fig. 3.

In general, the pulverizer illustrated includes a cylindrical upper housing section 10 and a lower housing section 11 supported on a foundation 12. The lower section encloses the pulverizer gear drive which includes a horizontal pinion shaft 13 arranged to drive a vertical drive shaft 14 axially arranged in the housing. The drive shaft 14 extends upwardly through bearings arranged to a base plate 15 forming the top of the lower housing section 11. The housing section 10 is detachably secured to the base plate 15 and encloses the grinding parts of the pulverizer which comprise a drive yoke 17 of general conical form keyed on the upper part of the drive shaft 14 and an annular grinding ring 18 supported on and doweled to a flattened lower portion of the drive yoke. The upper face of the grinding ring is shaped to form a circular track or race 19 for a row of rolling grinding elements 20, preferably balls of wear-resistant alloy. The ball row supports a non-rotating upper or top grinding ring 21 having a circular ball track 22 formed in its lower face and constructed and arranged as hereinafter described.

At four symmetrically spaced points, arms 23 project radially outwardly from the upper ring and are provided with sockets 24 for receiving dual purpose springs 25. Each spring is formed of a length of spring steel bar stock bent to form a single complete coil turn having a large pitch diameter. The upper ends of the springs 25 fit into corresponding sockets 26 carried by vertical adjusting bolts 27. Each bolt 27 is supported in a sleeve bracket 28 on the housing top plate 29 by means of a nut 30 and retainer 31. The springs 25 provide a resilient compressive force for the application of a grinding pressure upon the grinding rings and balls as well as a resilient torsional force restraining the rotational and radial movement of the top ring 21 relative to the axis of the bottom ring 18. This dual purpose spring construction is disclosed and claimed in a copending application of applicant Leach, Serial No. 783,248, filed October 31, 1947.

The raw material to be pulverized is supplied by a regulable table feeder 35 through an inclined feed spout 36 extending above the top grinding ring and discharging down the inner side thereof to the upper inclined surface of the yoke 17 at the inner side of the ball row. The inclined surface of the yoke and the rotation

thereof distributes the material circumferentially into the grinding zone. Due to the effect of centrifugal force the material flows outwardly into the ball race 19 where it is pulverized by the crushing action of the relatively moving grinding balls and rings and the attrition action of the particles on one another. The material is pulverized to various finenesses and discharges from the grinding zone at a high speed and tangentially to the periphery of the lower grinding ring, the velocity of discharge depending upon the rotational speed of the lower ring.

The pulverized material is removed from the grinding area by a high velocity annular stream 15 of a suitable gaseous carrier medium, preferably air, and when coal is being pulverized for combustion purposes, preferably the primary air supply used for combustion in the associated furnace. The air is supplied at a regulated temperature, e. g. 150-600° F., sufficient to eliminate substantially all of the surface moisture on the raw material undergoing pulverization. The air is preferably supplied under a superatmospheric pressure by a suitable forced draft fan (not shown) to an annular wind box 37 surrounding the lower part of the housing section 10. The carrier air passes through passages defined by equi-spaced obliquely arranged vanes 38 opening through the housing wall adjacent to the lower outer side of the lower grinding ring. The vanes 38 effect a swirling movement of the air stream in the same direction as the direction of lower ring rotation as it flows upwardly through the narrow annular passage between 35 the lower grinding ring and housing.

In accordance with the present invention, the lower grinding ring is provided with an annular vertical ledge 40 held in position thereon in any suitable manner, as by a welded extension plate 41 fitting between the yoke and lower ring. The ledge extends vertically to a level above the lower ring track sufficient to maintain the desired bed of material in the grinding track. For example, in one installation with balls 10½" diameter, the top of the ledge was 2¼" above the outer top face of the lower ring. In operation, the ledge will act as a dam over which the pulverized material will flow under centrifugal force, the space within the ledge being normally filled with material at an angle corresponding to the angle of the free surface of the forced vortex of the pulverizer material.

According to this invention, the swirling stream of carrier air has its velocity increased to a value at a pulverizer level corresponding to the upper end of the ledge, at which value, e. g. 9000-10,000 ft./min., substantially all of the pulverized material flowing over the ledge will be picked up and carried upwardly in suspension. For this purpose, a narrow outwardly inclined throat 42 is defined by parallel inverted frusto-conical plates 43 and 44, the stationary throat plate 43 being mounted on the housing wall by bolts 49 and extending inwardly and downwardly from the housing wall at the top level of the ledge, while the plate 44 is welded to and forms an angular extension of the ledge 40 substantially coextensive with the plate 43. The space between the upper ends of the plate 44 and ledge 40 is closed by an annular plate 45 across which the pulverized material flows to the throat 42. In one embodiment of the invention, the throat was ¾" in width and extended at an angle of substantially 30° to the vertical. The space between the lower end of the plate 43 and housing

wall is closed and an upwardly tapering entrance passage 47 for the throat formed by means of a frusto-conical extension 48 welded to the lower end of the plate 43 and arranged opposite the ledge area subjacent to the throat.

With the described throat construction and arrangement, the swirling air stream passes upwardly at a progressively increasing velocity through the passage 47 and on entering the throat 42 is directed outwardly at an acute angle to the housing wall, whereby the pulverized material flowing over and down the plate 45 is swept up by the air stream adjacent the housing wall and carried upwardly in suspension. The larger or denser particles swept up tend to drop out of the upflowing air stream and the stream of air along the housing wall tends to direct such particles inwardly towards the grinding zone. Any small particles of dense unpulverizable material, such as pyrites, will drop through the throat to the pulverizer space below the air entrance passages defined by the vanes 38 and be periodically discharged through a horizontally slideable gate 50 into a trap or compartment 51. The relative movement between the stationary plate 43 and rotating plate 44 effectively prevents clogging of the throat 42.

The material laden air stream swirls upwardly along the housing wall at the outer side of the top grinding ring and laterally to a rotary classifier 60 of the type disclosed in said U. S. Patent No. 2,275,595, except that the classifier blades are advantageously formed, as shown in Fig. 6, by circumferentially spaced vertical Z-bars 61 moving in the direction indicated. As disclosed in said prior patent, the classifier is arranged to extend across the lower end of the turret 62 in the top of which the pulverized material outlet 63 is located. The classifier is detachably mounted on and its rotation effected by a supporting structure 64 carried on the drive yoke 17. The supporting structure is provided with tangentially extending outlets 65, through which any material separating out within the classifier is returned to the inner side of the grinding ball row, mingling with the raw material therein from the feeder. Thus a major portion of the material to be pulverized, i. e. the raw material from the feeder 35 and the recirculated material from the classifier 60, is delivered to the grinding zone at the inner side of the ball row and flows outwardly through the grinding parts.

The classifier construction described effectively separates oversize particles in suspension in the air stream both by the mechanical action of the blades and the windage created by the moving blades. The desired fineness of output is indicated by the usual commercial guarantees of 99% through a U. S. Standard 50-mesh screen and 70% through a 200-mesh screen. The outer section of the Z-bars tends to deflect oversize particles outwardly away from the classifier and when their lateral movement is neutralized by the air stream, such particles will drop towards the grinding zone. Other oversize particles reaching the interblade area of the classifier are caught in the V-pockets formed by the blade middle and inner sections and slide to the bottom of the pockets and are then ejected by centrifugal force.

The oversize material so recirculated by the action of gravity and the classifier must be further pulverized before being fit for use. The recirculating load normally is many times the rate of discharge of the pulverized material from

the pulverizer outlet, e. g. when pulverizing bituminous coal, 20-30:1. While such material dropping into the space at the inner side of the ball row readily reaches the grinding zone, the portion heretofore dropping on and outside the upper grinding ring was greatly delayed in again reaching the grinding zone. According to the present invention, the re-entrance of recirculated material to the grinding zone is greatly facilitated by a special construction and arrangement of the upper grinding ring. As shown in Figs. 1-3, the upper ring is of vertically elongated cross-section with its major cross-sectional axis *a-a* upwardly and outwardly inclined and arranged substantially tangential to a ball radius at an angle of 45° in the upper inner quadrant of the grinding balls. The ring is so shaped that its ball contact is almost wholly confined to the upper inner ball quadrant and extends only a small arcuate distance beyond the ball vertical center line. For example, with 10½" diameter balls this distance was only ½" in one installation. The upper end of the ring cross-section is continuously curved and slopes downwardly at its inner side for a major portion of its extent at an angle of approximately 45° to the vertical with the remaining inner surface substantially vertical. The opposite face is arranged at an angle of approximately 30° to the vertical. With this formation the geometrical center *c* of the top ring will always be located at the inner side of the ball center line *b-b* during the normal life of the parts. A top ring construction having the desired strength, rigidity and life is thus provided. With this ring construction, substantially the whole upper outer octant surfaces of the balls and the intervening spaces are open to receive material dropping out of the air stream close to the point of initial pick-up, as indicated by the arrows in Fig. 3, or dropping downwardly through the space outside of the upper ring. The described relation of the balls and rings and recirculated material entrance area are not affected by the inevitable wear of the grinding parts.

The described primary recirculation effect is enhanced in the present construction by the location of stationary deflectors or plows 66 projecting inwardly from the housing wall at four symmetrically spaced locations adjacent the grinding zone. As shown in Figs. 3-5, each plow is sloped inwardly and upwardly in the direction of ring rotation at an angle of approximately 30° from the vertical and approximately 45° from the radial, so that it will extend at an angle across and immediately above the throat 42. With this construction the larger oversize particles discharging from the grinding zone which cannot be lifted by the air stream tend to impact on the plows and be deflected back into the upper part of the ball row, avoiding any tendency towards the formation of a slowly rotating suspended mass outside of the grinding zone.

As shown in Fig. 1, the portion of the throat plate 43 and extension 48 opposite the gate 50 is cut away at one segmental section to permit the installation of a counter-weighted relief gate 68 of the same contour and pivoted on a shaft 69 to allow large pieces of unpulverizable material, such as tramp iron, to drop into the subjacent part of the pulverizer.

The present invention has been found by field tests on bituminous coal to be adapted for successful use in all the sizes of pulverizers tested, i. e. pulverizers having different ball row pitch diameters and ball diameters. Comparative field

tests of two pulverizer sizes incorporating the present invention with the same pulverizers constructed as shown in said U. S. Patent 2,275,595 and said Leach application, Ser. No. 783,248 show the following superior performance attained by the present invention in pulverizing bituminous coal:

	Pat. 2,275,595	S. N. 783,248	Inven- tion
Pulverizer A:			10
Output, Percent	100	113	147.8
Fineness, Percent Passing 50 M.	96.0	97.5	99.0
Fineness, Percent Passing 200 M.	56.0	64.0	74.0
Static Press. Diff., Percent	100.0	98.6	90.2
Pulverizer B:			15
Output, Percent	100	104	138
Fineness, Percent Passing 50 M.	98.0	99.0	99.1
Fineness, Percent Passing 200 M.	68.0	72.0	73.0
Static Press. Diff., Percent	100.0	84.6	77.7

The greatly increased output with increased fineness and a decreased static pressure differential evidenced by the foregoing operating results are believed to be mainly due to the improved conditions in and adjacent to the grinding zone. These conditions are attained by preventing carrier air flow directly into the ball row and thus avoiding aeration and consequent fluidizing of material at the time of pulverization; the maintenance of a bed of material on the grinding face of sufficient thickness to cause adequate pulverization on each passage of a particle through the grinding zone; the rapid scavenging of the undersize particles from the material leaving the grinding zone to prevent overgrinding and consequent useless power consumption, the recirculation of much of the oversize material to the grinding zone by the shortest practical route, i. e. so as to back feed the balls above their horizontal center line; the elimination of a dense mass of oversize material around the grinding zone; and the intimate mixing of the hot air and partially pulverized material at a point in the circulation path which insures proper drying of the material. The improved construction has been found to successfully handle extremely fine sizes of raw coal which previously were considered unusable and to increase the permissible operating load range from 2.5:1 to 9:1 with substantially complete freedom from trap discharge.

While in accordance with the provisions of the statutes we have illustrated and described herein the best form of the invention now known to us, those skilled in the art will understand that changes may be made in the form of the apparatus covered by our claims, and that certain features of our invention may sometimes be used to advantage without a corresponding use of other features. In the claims, the word "air" is intended to cover generically air and any other gaseous carrier medium suitable for conveying pulverized material in the manner described.

We claim:

1. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls to sweep up pulverized material discharging therefrom, said air flow di-

recting means being constructed and arranged to define an annular throat inclined upwardly and outwardly away from said row of grinding balls, and said upper grinding ring being cut away at its outer side to an extent sufficient to lay open a major portion of the upper outer quadrant of said grinding balls for the reception of recirculated material and its lower surface in contact with said balls over a substantially greater arcuate portion of the upper inner quadrant of said balls than its contact with the upper outer quadrant of said balls.

2. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls to sweep up pulverized material discharging therefrom, said air flow directing means being constructed and arranged to define an annular throat inclined upwardly and outwardly to a point adjacent said housing so as to deflect the air stream away from said row of grinding balls, and said upper grinding ring being cut away at its outer side to an extent sufficient to lay open substantially all of the upper outer quadrant of said grinding balls for the reception of recirculated material.

3. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls to sweep up pulverized material discharging therefrom, said air flow directing means including an annular stationary throat plate constructed and arranged relative to said lower grinding ring to define therebetween an annular throat inclined upwardly and outwardly to a point adjacent said housing so as to deflect the air stream away from said row of grinding balls, and said upper grinding ring being cut away at its outer side to an extent sufficient to lay open a major portion of the upper outer quadrant of said grinding balls for the reception of recirculated material and its lower surface in contact with said balls over a substantially greater arcuate portion of the upper inner quadrant of said balls than its contact with the upper outer quadrant of said balls.

4. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means forming a peripheral ledge on and extending substantially above the ball-contacting surface of said lower grinding ring, means for directing an annular stream of air upwardly past the outer side of said grinding rings and row of grinding balls to sweep up pulverized material discharging therefrom, said air flow directing means in-

cluding an annular stationary throat plate constructed and arranged relative to said ledge-forming means to define therebetween an annular throat inclined upwardly and outwardly away from said row of grinding balls, and said upper grinding ring being cut away at its outer side to an extent sufficient to lay open a major portion of the upper outer quadrant of said grinding balls for the reception of recirculated material.

5. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls to sweep up pulverized material discharging therefrom, said air flow directing means being constructed and arranged to define an annular throat inclined upwardly and outwardly away from said row of grinding elements and terminating at its upper end at the material discharge level of said lower grinding ring.

6. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means forming a peripheral ledge on and extending above the upper surface of said lower grinding ring, means for directing an annular stream of air upwardly past the outer side of said grinding rings and row of grinding balls to sweep up pulverized material discharging therefrom, said air flow directing means including an annular stationary throat plate constructed and arranged relative to said ledge-forming means to define therebetween an annular throat inclined upwardly and outwardly at an acute angle to and terminating adjacent said housing so as to deflect the air stream away from said row of grinding balls, and said upper grinding ring being cut away at its outer side to an extent sufficient to lay open substantially all of the upper outer quadrant of said grinding balls and interball spaces for the reception of recirculated material, and a circumferential series of stationary plow members mounted on said housing opposite said row of grinding balls and adjacent the upper end of said throat and projecting inwardly in the direction of lower ring rotation at an angle to said housing sufficient to deflect pulverized material into the upper part of said row of grinding balls.

7. A pulverizer comprising a housing enclosing a rotary lower grinding ring, means for rotating said lower grinding ring, a circular row of rolling grinding elements supported on said lower grinding ring, a non-rotary upper grinding ring sup-

ported on said grinding elements, means for delivering material to be pulverized mainly to the inner side of said row of grinding elements, peripheral ledge means on said lower grinding ring arranged to provide a material discharge level therefrom substantially above the level of the ball contacting area thereof, and means for directing an annular stream of air upwardly past the outer side of said grinding rings and row of grinding elements to sweep up pulverized material discharging therefrom, said air flow directing means being constructed and arranged to define an annular throat inclined upwardly and outwardly away from said row of grinding elements and terminating at its upper end at the material discharge level of said lower grinding ring.

8. A pulverizer comprising a housing enclosing a rotary lower grinding ring, means for rotating said lower grinding ring, a circular row of rolling grinding elements supported on said lower grinding ring, a non-rotary upper grinding ring supported on said grinding elements, means for delivering material to be pulverized mainly to the inner side of said row of grinding elements, means for directing an annular stream of air upwardly past the outer side of said grinding rings and row of grinding elements to sweep up pulverized material discharging therefrom, said air flow directing means including an annular stationary throat plate constructed and arranged relative to the outer periphery of said lower grinding ring to define therebetween an annular throat inclined upwardly and outwardly to a point adjacent said housing and terminating at its upper end at the material discharge level of said lower grinding ring so as to deflect the air stream away from said row of grinding elements.

9. A pulverizer comprising a housing enclosing a lower rotary grinding ring, means for rotating said lower grinding ring, a circular row of rolling grinding elements supported on said lower grinding ring, a non-rotary upper grinding ring supported on said grinding elements, means for delivering material to be pulverized mainly to the inner side of said row of grinding elements, means forming a peripheral ledge on and extending above the upper surface of said lower grinding ring, means for directing an annular stream of air upwardly past the outer side of said grinding rings and row of grinding elements to sweep up pulverized material discharging therefrom, said air flow directing means including an annular stationary throat plate constructed and arranged relative to said ledge-forming means to define therebetween an annular throat inclined upwardly and outwardly to a point adjacent said housing and terminating at its upper end at the level of said ledge so as to deflect the air stream away from said row of grinding elements.

10. A pulverizer comprising a housing enclosing a lower rotary grinding ring, means for rotating said lower grinding ring, a circular row of rolling grinding elements supported on said lower grinding ring, a non-rotary upper grinding ring supported on said grinding elements, means for delivering material to be pulverized mainly to the inner side of said row of grinding elements, means forming a peripheral ledge on and extending above the upper surface of said lower grinding ring, means for directing an annular stream of air upwardly past the outer side of said grinding rings and row of grinding elements to sweep up pulverized material discharging therefrom, said air flow directing means including an annular stationary throat plate constructed and ar-

ranged relative to said ledge-forming means to define therebetween an annular throat inclined upwardly and outwardly at an acute angle to and terminating at its upper end adjacent said housing and at the level of said ledge so as to deflect the air stream away from said row of grinding elements.

11. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls to sweep up pulverized material discharging therefrom, said air flow directing means including an annular stationary throat plate and being constructed and arranged to define an annular throat inclined upwardly and outwardly at an acute angle to and terminating at its upper end adjacent said housing and at the material discharge level of said lower grinding ring so as to deflect the air stream away from said row of grinding balls, and a circumferential series of stationary plow members mounted on said housing opposite said row of grinding balls and adjacent the upper end of said throat and projecting inwardly in the direction of lower ring rotation at an angle to said housing sufficient to deflect pulverized material into the upper part of said row of grinding balls.

12. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means forming a peripheral ledge on and extending above the upper surface of said lower grinding ring, means for directing an annular stream of air upwardly past the outer side of said grinding rings and row of grinding balls to sweep up pulverized material discharging therefrom, said air flow directing means including an annular stationary throat plate constructed and arranged relative to said ledge-forming means to define therebetween an annular throat inclined upwardly and outwardly at an acute angle to and terminating at its upper end adjacent said housing and at the level of said ledge so as to deflect the air stream away from said row of grinding balls, and a circumferential series of stationary plow members mounted on said housing opposite said row of grinding balls and adjacent the upper end of said throat and projecting inwardly in the direction of lower ring rotation at an angle to said housing sufficient to deflect pulverized material into the upper part of said row of grinding balls.

13. A pulverizer comprising a housing enclosing a rotary lower grinding ring, means for rotating said lower grinding ring, a circular row of grinding balls supported on said lower grinding ring, a non-rotary upper grinding ring having a concavely curved lower surface contacting with and supported on said grinding balls, means for delivering material to be pulverized mainly to the inner side of said row of grinding balls, means for directing an annular stream of air upwardly past the outer side of said grinding rings and row of grinding balls so as to sweep up pulverized ma-

terial discharging therefrom, and said upper grinding ring being cut away at its outer side to an extent sufficient to lay open a major portion of the upper outer quadrant of said grinding balls for the reception of recirculated material and its lower surface in contact with said balls over a substantially greater arcuate portion of the upper inner quadrant of said balls than its contact with the upper outer quadrant of said balls.

14. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said lower grinding ring so as to sweep up pulverized material discharging therefrom, and said upper grinding ring being cut away at its outer side to an extent sufficient to lay open substantially all of the upper outer octant surfaces of said grinding balls and interball spaces for the reception of recirculated material.

15. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized mainly to the inner side of said row of grinding balls, means for directing an annular stream of air upwardly past the outer side of said grinding rings and row of grinding balls so as to sweep up pulverized material discharging therefrom, and said upper grinding ring being cut away at its outer side to an extent sufficient to lay open a major portion of the upper outer quadrant of said grinding balls for the reception of recirculated material and having its lower surface in contact with said balls over a substantially greater arcuate portion of the upper inner quadrant of said balls than its contact with the upper outer quadrant of said balls and its geometrical center located at the inner side of the vertical center line of said grinding balls.

16. A pulverizer non-rotary upper grinding ring adapted to be supported on a circular row of grinding balls arranged to receive material to be pulverized at the inner side of said row, said upper grinding ring having an arcuate ball-contacting surface on its underside, the major portion of the outer side of the ring, extending from the outer end of said arcuate surface, lying in an inverted conical surface of revolution whose semi-vertex angle is not greater than approximately 30° to expose a major portion of the upper outer octant surfaces of said grinding balls when positioned thereon and being free of inwardly projecting parts at the inner side thereof, the outer periphery of said arcuate ball contacting surface being substantially higher than the inner periphery thereof.

17. A pulverizer non-rotary upper grinding ring adapted to be supported on a circular row of grinding balls, said upper grinding ring having a lower arcuate ball-contacting surface and being cut away at its outer side from the outer end of said arcuate surface to an extent sufficient to expose substantially all of the upper outer octant surfaces of said grinding balls, be-

ing free of projecting parts at the inner side thereof, and having its major cross-sectional axis upwardly and outwardly inclined and its geometrical center at the inner side of the vertical center line of said grinding balls when positioned thereon.

18. A pulverizer comprising a housing enclosing a rotary lower grinding ring, means for rotating said lower grinding ring, a circular row of grinding balls supported on said lower grinding ring, a non-rotary upper grinding ring supported on said grinding balls, means for delivering material to be pulverized to said row of grinding balls, means forming a peripheral ledge on and extending substantially above the ball-contacting surface of said lower grinding ring, means for directing an annular stream of air upwardly past the outer side of said lower grinding ring to sweep up pulverized material discharging therefrom, said air flow directing means including an annular stationary throat plate constructed and arranged relative to said ledge-forming means to define therebetween an annular throat, and said upper grinding ring being cut away at its outer side to an extent sufficient
